CLAIM

We claim the ornamental design for a portable printer, as shown and described.

DESCRIPTION

FIG. 1 is a top perspective view of a portable printer showing our new design;

FIG. 2 is an enlarged top view thereof;

FIG. 3 is a bottom view of FIG. 2;

FIG. 4 is a left-side view of FIG. 2;

FIG. 5 is a right-side view of FIG. 2;

FIG. 6 is a rear view of FIG. 2; and,

FIG. 7 is a front view of FIG. 2.

The broken lines in the drawing figures show environmental subject matter, and form no part of the claimed design.
